UNITED STATES PATENT OFFICE.

ROBERT SCHEANBLUM AND GRACE SCHEANBLUM, OF DANBURY, CONNECTICUT.

COMBINED HAIR FOUNDATION AND SWITCH-ATTACHING DEVICE.

1,365,549.

Specification of Letters Patent. Patented Jan. 11, 1921.

Application filed March 12, 1920. Serial No. 365,195.

To all whom it may concern:

Be it known that we, ROBERT SCHEANBLUM and GRACE SCHEANBLUM, citizens of the United States of America, residing at Danbury, in the county of Fairfield and State of Conn., have invented certain new and useful Improvements in Combined Hair Foundations and Switch-Attaching Devices, of which the following is a specification.

10 The invention relates to improvements in hair dressing foundations, and it is particularly adapted for use in producing in the hair a roll effect.

It has been proposed in the prior art to 15 employ a foundation of an openwork material, but practice has demonstrated that it is frequently necessary for the user in order to give the hair an attractive appearance, to employ a switch or other false hair. In using 20 the prior art structures considerable difficulty has been experienced in properly uniting the switch to the foundation so as to enable the switch to be properly rolled thereover and retained in position after the foundation 25 has been placed in the hair.

The present invention therefore broadly comprehends a combined foundation and switch attaching device. It is an object of the invention to provide a foundation formed 30 with a suitable hook as a continuation of the material of the foundation adapted to receive the tape of the switch or the like, to retain the same in position on the support when the switch is wrapped therearound.

35 From a more specific aspect, the invention comprises a foundation having a base which is slightly curved, and suitable hair supporting elements in combination with a hook formed of the material of the foundation adapted to receive the loop of a switch which is then wrapped upon the foundation that is to be applied to the hair of the user.

40 While the invention is disclosed as being applied to a foundation for producing a roll effect, it is of course applicable to other forms of hair supports with ease.

In the drawings, Figure 1 represents a view of the device as applied to the hair.

Fig. 2 is a top view.

50 Fig. 3 is a side view; and,
Fig. 4 is an end view.

Referring now more particularly to the

drawings wherein like reference characters indicate corresponding parts the numeral 1 designates the base of the support, which is 55 of a slightly bowed formation being disclosed as of a rectangular shape. The support has extending therefrom a central hair support 2 and a cross support 3. The hair support 2 is a continuation of the base 1 passing through a loop 4 in the base and then thereacross to be united to the opposite side of the base by a twisting thereof. Both the supports 2 and 3 are of a bowed formation and of an elevation materially greater than 60 the elevation of the base 1. The support 3 is composed of a piece of material separate from that of the base 1 and support 2, being looped around the support 2 and at its opposite end twisted to form a hook 5. This hook 65 is adapted to receive the loop 6 of a switch 7, it being appreciated that a switch is usually provided with a piece of material of a relatively hard nature generally known as the tail of the switch. In using the device the 70 loop of the switch is secured to the hook 5, and the tail thereof passed under the base of the foundation as disclosed in Fig. 1, after which the switch is wrapped around the support or foundation to be then incorporated 75 in the hair of the user. It is apparent that by utilizing the hook 5, the switch is always maintained in position, and it is an impossibility for the switch to become disengaged from the foundation when the same has been 80 rolled thereon.

While the switch attaching device is shown in the accompanying drawings in the nature of a hook, it will be understood that the same is subject to other changes so long as a quick 85 detachable form of attachment is provided to enable the loop of the switch to be united to the support and to retain the switch thereon when the same is rolled over the support.

Having thus described the invention what 90 we claim is:

1. A hair foundation comprising a base, and hair supports connected therewith extending above said base, of a switch attaching hook disposed adjacent the base and 100 adapted to receive the loop of a switch first passing under the base and then to be wrapped around said foundation, the open ended portion of the hook facing upwardly

and being disposed at an angle relative to the base.

2. A hair foundation comprising a wire base, and wire supports carried by said base,
5 the material of the base being twisted to form a switch attaching hook opening at the upper portion of the hook to receive the

switch supporting loop, said hook being disposed at an acute angle relative to the base.

In testimony whereof we affix our sig- 10 natures.

ROBERT SCHEANBLUM.
GRACE SCHEANBLUM.
